UNITED STATES PATENT OFFICE.

JOHN HAYS HAMMOND, JR., OF GLOUCESTER, MASSACHUSETTS.

EMERGENCY LAUNCHING SYSTEM FOR TORPEDOES.

1,347,092.

Specification of Letters Patent. Patented July 20, 1920.

Application filed June 1, 1916, Serial No. 101,107. Renewed October 9, 1919. Serial No. 329,648.

To all whom it may concern:

Be it known that I, JOHN HAYS HAMMOND, Jr., a citizen of the United States, and a resident of Gloucester, county of Essex, and State of Massachusetts, have invented a certain new and useful Emergency Launching System for Torpedoes, of which the following is a specification.

One of the objects of this invention is to provide an emergency system for automatically launching a torpedo from a torpedo boat when any vital portion of the boat is pierced by a projectile.

In the accompanying drawings Figure 1 is a diagrammatic top plan view of a torpedo boat provided with an emergency system constructed in accordance with this invention for launching a torpedo; and Fig. 2 is an enlarged fragmentary horizontal section showing the result when a projectile pierces the protective inclosure forming a portion of this invention.

Referring to the drawings, this invention is shown in one of its forms as applied to a torpedo boat 5, which is driven by any suitable propeller 6, actuated by any suitable means as, for instance, by an internal combustion engine 7. The boat is also provided with the usual or any suitable torpedo tube 11 arranged to contain a torpedo 12. For launching the torpedo 12 from the tube 11 a tank 13, containing compressed air, is arranged in the boat and a pipe 16 leads from the tank 13 through a valve 17 and into the inner end of the torpedo tube 11. The valve 17 is controlled by an electromagnet 20 which when energized causes the valve to open and to admit compressed air from the tank 13 into the inner end of the torpedo tube 11 to force the torpedo 12 out of the tube. The electromagnet 20 is provided with two windings, one of which is in a circuit 23 including a switch 24 and a battery 25, and which is controlled in any well known or suitable manner by suitable wireless receiving apparatus 26, which is provided therefor upon the boat so that the launching of the torpedo 12 may be controlled by radiant energy transmitted from a distant station. The wireless receiving apparatus 26 may also be arranged in a well known manner to control the direction of movement of the boat through a suitable conduit 27 controlling well known or suitable connections (not shown) with a rudder 28.

For automatically causing the launching of the torpedo 12 when a projectile pierces a vital portion of the boat, as for instance the portion of the boat containing the engine 7, or the portion of the boat containing the wireless receiving apparatus 26, these vital portions of the boat are inclosed by two spaced walls made of conducting material such, for instance, as mild sheet steel. 60 In the form of this invention shown in the drawings the engine 7 and the wireless receiving apparatus 26 are each surrounded by separate inclosures of this character, the engine 7 being surrounded by an oblong rectangular inclosure comprising two outer vertical sides walls 30 and 31, two outer vertical end walls 32, 33, two inner vertical side walls 34, 35, and two inner vertical end walls 36 and 37. The outer walls 30, 31, 70 32 and 33 form a continuous casing, and the inner walls 34, 35, 36 and 37 also form a continuous casing, and these casings are spaced slightly apart and are insulated one from the other by suitable vertical strips of 75 insulation 40, and these walls 30 to 37 are insulated from the boat 5. 80

The wireless receiving apparatus 26 is also surrounded by an outer casing comprising two vertical side walls 50 and 51 85 and two vertical end walls 52 and 53, and by an inner casing comprising two vertical side walls 54 and 55, and two vertical end walls 56 and 57, all these walls being made of any suitable conducting sheet material 90 such for instance, as mild sheet steel, and the outer casing 50, 51, 52 and 53 being spaced slightly from and insulated from the inner casing 54, 55, 56 and 57 by means of suitable strips of insulation 60, and both of 95 these casings being insulated from the boat.

Any other vital portions of the boat 5 might be similarly surrounded by inner and outer casings of sheet metal, or all of the vital portions of the boat might be surrounded by a single inclosure consisting of inner and outer casings of sheet metal insulated from each other and from the boat. 100

In the form of this invention shown in the drawings the outer casing surrounding the engine 7 is connected to one end of a conductor 65 which leads to one pole of a battery 66, the other pole of which is connected through a switch 66' to a conductor 67 which includes one coil of the electromagnet 20 and which is terminally connected to the inner casing surrounding the engine 105 110

7, and by a branch wire 68 to the inner casing surrounding the wireless receiving apparatus 26. Normally no current flows through the battery 66 and its coil on the electromagnet 20, as there is normally no electrical connection between the outer casings and the inner casings surrounding the engine 7 and the wireless receiving apparatus 26, but when a bullet pierces the outer 5 and inner casing which surrounds the engine 7 or the outer and inner casing which surrounds the wireless receiving apparatus 26, as illustrated for instance in Fig. 2 where a projectile 75 is shown piercing the side 10 walls 51 and 55 surrounding the wireless receiving apparatus, then the circuit is closed through the battery 66 thus energizing the electromagnet 20 and causing air to be admitted from the tank 15 into the torpedo tube 11 to force the torpedo 12 out of the tube.

Although only a single form is shown in which this invention may be embodied, it is understood that this invention is not limited to any specific construction but might be applied in various forms without departing from the spirit of the invention or the scope of the appended claims.

Having thus fully described this invention, I claim and desire to protect by Letters Patent of the United States:

1. A marine vessel having a support adapted to receive a torpedo, and in combination with said support, torpedo launching means, and means including a normally open electric circuit including spaced conducting plates capable of closing said circuit when they are pierced by a discharged projectile to render said torpedo launching means active for the launching of the torpedo.

2. A marine vessel having a support adapted to receive a torpedo, and in combination with said support, pneumatic torpedo launching means, and means including a normally open electric circuit including spaced conducting plates forming a part of the marine vessel structure, said plates being capable of closing said circuit when they are pierced by a discharged projectile to cause the automatic launching of the torpedo.

3. The combination with a support adapted to hold a torpedo, of means for launching a torpedo from said support, and means including a normally open electric circuit containing spaced conducting plates arranged to control said launching means, said open circuit being arranged to be closed by the piercing of said plates by a projectile of conducting material.

4. The combination with a support adapted to hold a torpedo, of means for launching a torpedo from said support, means responsive to radiant energy for controlling said

launching means, and means operable independently of said first mentioned controlling means and arranged to be actuated by the movement of a projectile for causing the launching of a torpedo from said support.

5. The combination with a support adapted to hold a torpedo, of means for launching a torpedo from said support including a normally open electric circuit containing spaced sheet conductors, said open circuit being arranged to be closed as a result of the piercing of said conductors by a conducting projectile.

6. The combination with a torpedo boat, of a support carried by said boat and adapted to hold a torpedo, means for launching a torpedo from said support, means responsive to radiant energy for controlling said launching means, and means operable independently of said first mentioned controlling means and including a normally open electric circuit containing spaced conducting plates for controlling said launching means.

7. The combination with a movable body, of a support carried thereby for holding a torpedo, means for launching a torpedo from said support, receiving means carried by said body and responsive to radiant energy to control said launching means, and means for controlling said launching means independently of said receiving means and comprising a normally open electric circuit containing spaced conducting plates arranged adjacent said receiving means.

8. The combination with a movable body, of means carried thereby for propelling the same, a support carried by said body and arranged to hold a torpedo, means for launching a torpedo from said support, receiving means carried by said body and responsive to radiant energy to control said launching means, and means including spaced conducting plates arranged adjacent said propelling means and said receiving means for controlling said launching means.

9. The combination with a movable body, with means carried thereby for propelling the same, a support carried by said body for holding a torpedo, receiving means responsive to radiant energy carried by said body and arranged to control said launching means and also the direction of movement of said body, and means including a normally open electric circuit containing spaced conducting plates operable independently of said receiving means for controlling said launching means, said open circuit being arranged to be closed as the result of the piercing of said conducting plates by a projectile.

10. The combination with a support adapted to hold a torpedo, of means for launching a torpedo from said support, and

means including a normally open electric circuit containing spaced conducting elements arranged to control said launching means, said open circuit being arranged to be closed by the piercing of said elements by a projectile of conducting material to cause a torpedo to be launched from said support.

11. The combination with a support adapted to hold a torpedo, of means for launching a torpedo from said support, and means including a normally open electric circuit containing spaced conducting surfaces arranged to control said launching means, said open circuit being arranged to be closed by the piercing of said surfaces by a projectile of conducting material to cause a torpedo to be launched from said support.

12. The combination with a support adapted to hold a torpedo, of means for launching a torpedo from said support, and means including a normally open electric circuit containing spaced conducting screens arranged to control said launching means, said open circuit being arranged to be closed by the piercing of said screens by a projectile of conducting material to cause a torpedo to be launched from said support.

13. The combination with a support adapted to hold a torpedo, of means for

launching a torpedo from said support, and means including a normally open electric circuit containing spaced conducting screens arranged to control said launching means, said open circuit being arranged to be closed by the piercing of said screens by a projectile of conducting material to cause a torpedo to be launched from said support, each of said screens covering a considerable area, and said screens being spaced apart a distance less than the length of the ordinary projectile used in warfare.

14. The combination with a support adapted to hold a body to be projected, of means for projecting said body from said support, and means including a normally open electric circuit containing spaced conducting elements arranged to control said projecting means, said open circuit being arranged to be closed by the piercing of said elements by a projectile of conducting material to cause said body to be projected from said support.

Signed at Gloucester in the county of Essex and State of Massachusetts this 26th day of May A. D. 1916.
